(57) **CLAIM**

The ornamental design for an base part of an electronic
vaping device, as shown and described.

DESCRIPTION

FIG. 1 is a front-top perspective view of a base part of an
electronic vaping device according to a first embodiment;
FIG. 2 is a front view of a base part of an electronic vaping
device shown in FIG. 1;

FIG. 3 is a rear view of a base part of an electronic vaping
device shown in FIG. 1;

FIG. 4 is a left side view of a base part of an electronic vaping
device shown in FIG. 1;

FIG. 5 is a right side view of a base part of an electronic vaping
device shown in FIG. 1;

FIG. 6 is a top view of a base part of an electronic vaping
device shown in FIG. 1;

FIG. 7 is a bottom view of a base part of an electronic vaping
device shown in FIG. 1;

FIG. 8 is a rear-bottom perspective view of a base part of an
electronic vaping device shown in FIG. 1;

FIG. 9 is a front-top perspective view of a base part of an
electronic vaping device according to a second embodiment;
FIG. 10 is a front view of a base part of an electronic vaping
device shown in FIG. 9;

FIG. 11 is a rear view of a base part of an electronic vaping
device shown in FIG. 9;

FIG. 12 is a left side view of a base part of an electronic vaping
device shown in FIG. 9;

FIG. 13 is a right side view of a base part of an electronic vaping
device shown in FIG. 9;

FIG. 14 is a top view of a base part of an electronic vaping
device shown in FIG. 9;

FIG. 15 is a bottom view of a base part of an electronic vaping
device shown in FIG. 9;

(Continued)

FIG. 16 is a rear-bottom perspective view of a base part of an electronic vaping device shown in FIG. 9;
 FIG. 17 is a front-top perspective view of a base part of an electronic vaping device according to a third embodiment;
 FIG. 18 is a front view of a base part of an electronic vaping device shown in FIG. 17;
 FIG. 19 is a rear view of a base part of an electronic vaping device shown in FIG. 17;
 FIG. 20 is a left side view of a base part of an electronic vaping device shown in FIG. 17;
 FIG. 21 is a right side view of a base part of an electronic vaping device shown in FIG. 17;
 FIG. 22 is a top view of a base part of an electronic vaping device shown in FIG. 17;
 FIG. 23 is a bottom view of a base part of an electronic vaping device shown in FIG. 17;
 FIG. 24 is a rear-bottom perspective view of a base part of an electronic vaping device shown in FIG. 17;
 FIG. 25 is a front-top perspective view of a base part of an electronic vaping device according to a fourth embodiment;
 FIG. 26 is a front view of a base part of an electronic vaping device shown in FIG. 25;
 FIG. 27 is a rear view of a base part of an electronic vaping device shown in FIG. 25;
 FIG. 28 is a left side view of a base part of an electronic vaping device shown in FIG. 25;
 FIG. 29 is a right side view of a base part of an electronic vaping device shown in FIG. 25;
 FIG. 30 is a top view of a base part of an electronic vaping device shown in FIG. 25;
 FIG. 31 is a bottom view of a base part of an electronic vaping device shown in FIG. 25; and,
 FIG. 32 is a rear-bottom perspective view of a base part of an electronic vaping device shown in FIG. 25.
 The tapered end portion of the mouthpiece having the oval opening can be opaque, transparent or semitransparent. The shading lines in the figures show contour and not surface ornamentation.
